(57) **CLAIM**

The ornamental design for a pillowcase with integrated device holder pouch and charging cord aperture, as shown and described.

DESCRIPTION

FIG. 1 is a front perspective view of a new design for a pillowcase with integrated device holder pouch and charging cord aperture.

FIG. 2 is a top view of a new design for a pillowcase with integrated device holder pouch and charging cord aperture. FIG. 3 is a rear view of a new design for a pillowcase with integrated device holder pouch and charging cord aperture. FIG. 4 is a right side view of a new design for a pillowcase with integrated device holder pouch and charging cord aperture.

FIG. 5 is a left side view of a new design for a pillowcase with integrated device holder pouch and charging cord aperture.

FIG. 6 is a top view of a new design for a pillowcase with integrated device holder pouch and charging cord aperture; and,

FIG. 7 is a bottom view of a new design for a pillowcase with integrated device holder pouch and charging cord aperture.

The broken lines depict portions of the pillowcase with integrated device holder pouch and charging cord aperture that form no part of the claimed design.
